HINGE

Theodore Ulrich, Milwaukee, Wis., assignor to
 Nash-Kelvinator Corporation, Kenosha, Wis.,
 a corporation of Maryland

Application October 4, 1941, Serial No. 413,608

12 Claims. (Cl. 16—135)

This invention relates to a hinge and more particularly to a hinge useful in hanging automobile doors.

It is an object of the present invention to provide a door stay hinge which will function to hold a door in open position and which will also function to urge the door to closed position as it approaches such position to prevent the accidental opening thereof by gravity or other light forces, such stay hinge functioning, moreover, to keep a door propped open in either a fully opened or partially opened position.

It is also an object of the invention to provide a door check which functions in two positions of the door to keep the door propped open.

It is also an object of the invention to provide a limit stop of substantial character which will be sturdy enough to prevent damage to the door or its hinges when the door is violently opened.

Other objects and advantages of this invention will appear hereinafter as the description proceeds and will be particularly pointed out in connection with the appended claims.

In the drawings, of which there are two sheets:

Figure 1 is a horizontal sectional view through a door and an associated door pillar of an automobile showing the hinge of the present invention applied thereto and with the hinge and door in closed position;

Figure 2 is a vertical sectional view through a portion of the door pillar shown in Figure 1 but with the door omitted;

Figure 3 is a horizontal sectional view through the hinge shown in Figure 2, showing the hinge in closed position, taken upon a plane as indicated by the line 3—3 of Figure 2 and looking in the direction of the arrows;

Figure 4 is a horizontal sectional view through the hinge taken upon a plane as indicated by the line 4—4 of Figure 2 and looking in the direction of the arrows and also showing the hinge in closed position;

Figure 5 is a vertical sectional view corresponding to Figure 3 showing the hinge in the half open position;

Figure 6 is a vertical sectional view corresponding to Figure 4 but showing the hinge in its half open position;

Figure 7 is a horizontal sectional view corresponding to Figure 3 and showing the hinge in its fully open position; and

Figure 8 is a horizontal sectional view corresponding to Figure 4 but showing the hinge in its fully open position.

Referring more particularly to the drawings,

in which similar parts are designated by similar reference characters, the device is shown to be employed in an automobile body, one of the outer panels of which appears at 10. The outer panel 10 may be secured as by welding or other similar means to a door pillar 12 made up of a generally channel shaped element 14 which has its open end closed by a plate 16. Within the box section formed by the door pillar 12, there is secured the base portion 18 of the door hinge forming the subject matter of the present invention. The base member 18 is generally of U or channel shape and is provided with outturned flanges 17 by means of which it is secured to the door pillar 12 by any suitable instrumentalities. Flanges 17 may be covered with an escutcheon plate 19 to which the flanges 17 are secured and which is provided with an aperture 21 to pass the hinge leaf 28. The base member 18 is provided adjacent the bottom of the U with parallelly-disposed, inwardly-dished portions 20 which are pierced to receive a pivot pin 22. The pivot pin 22 extends through washers 24 adjacent the dished portions 20 and through the inner thickened portion 26 of a hinge leaf 28 which is pierced in its outer portion at 30 in order to secure the same to the interior of the door assembly 32.

The U-shaped base member 18 has its sides reinforced and additionally secured to one another by means of a brace element 34 generally of U-shape which spans the space between the sides of the base 18 and is suitably secured thereto as by the spot welding 36. The strap or brace 34 has an additional function which will be later explained.

It will be noted that the hinge leaf 28 is provided intermediate its ends with a re-entrant bend 38, the function of this bend being to permit hinging of the door as close as possible to the outer wall of the vehicle without interfering with the proper functioning of the hinge. It will be understood that the hinge leaf 28 may assume a variety of shapes without departing from the spirit of the invention.

The hinge base 18 is provided upon the right side 40 as viewed in Figure 2 and as shown in Figure 4 with an arcuate slot 42 which receives one end 44 of the hairpin spring 46. Such end 44 extends at right angles to the general plane of the spring 46, the opposite end 48 of the spring 46 extending parallel but in an opposite direction to the end 44 and being seated in a drilled aperture 49 upon the right side of the hinge leaf 28.

The left side wall 50 of the base 18 as viewed

55 in Figure 2 is provided with a straight slot 52

having rounded ends for the reception of the upper end 54 of a hairpin spring 56, such end extending at right angles to the general plane of the spring 56. The lower end 58 of the spring 56 extends parallel but in an opposite direction to the end 54 and is seated within an aperture 60 formed in the left side of the hinge leaf 28.

It will be noted that the leaf 28 is shown in Figures 3 and 4 in the closed position of the hinge and that in this position the end 54 of the spring 56 has loose engagement with the slot 52 while the end 44 of the spring 46 upon the right side of the hinge is under slight initial compression between the slot 42 and anchorage 49 so that a slight force is exerted upon the hinge leaf 28 in a direction to rotate the hinge leaf 28 in a counterclockwise direction (as viewed in Figure 4) about the pivot pin 22. Motion of the hinge leaf 28 in a counterclockwise direction as view in Figure 4 is prevented due to the engagement of the door 32 of the automobile with the door jamb and its latching instrumentalities.

As the door is moved from its closed position in being opened, the springs 46 and 56 function as follows: It will be appreciated that the hinge 28 as shown in Figures 3, 5 and 7, moves in a counter-clockwise direction to open and, as shown in Figures 4, 6 and 8, (which figures are sections taken upon a plane looking in the opposite direction from Figures 3, 5 and 7) moves in a clockwise direction to open. The first portion of the opening movement results in moving the end 54 of spring 56 upwardly in the slot 52 because of the upward motion of end 58 with the hinge leaf 28 in rotating about the pivot pin 22.

At the same time upward movement of the end 48 of spring 46 results in a shortening or diminution of the distance between the ends 44 and 48 of the spring 46 due to the fact that end 44 is confined against further outward movement within the arcuate slot 42 while end 48 is rotated about pin 22 closer to the outer end of slot 42. Accordingly, the spring 46 as shown in Figure 4 must pass through a dead center position in which the axes of the ends 44 and 48 are aligned with the axis of the pivot pin 22. When the dead center position just referred to is passed, the spring then exerts a force tending to rotate the hinge leaf 28 in a clockwise direction as viewed in Figure 4 and will continue to exert such a force until the energy of the spring is relieved or until some intervening force acts upon it.

In the case of the present hinge, the intervening force mentioned above takes the form of the cooperating spring 56 which, when it reaches the upper end of the slot 52, at approximately the same time as dead center position is reached upon the axes of parts 44, 48 and 22 is placed under tension by the seating of the end 54 at the upper end of the slot 52. When an equal stressing or balance between the springs 46 and 56 is attained, the hinge leaf 28 will come to rest. This position corresponds roughly to the half open position of the car door 32.

Upon further opening movement of the door, spring 56 is further compressed as the centers of the ends 54 and 58 of spring 56 approach one another and pass through the dead center position of the axes of the ends 54 and 58 and of the pivot pin 22. After passing through this dead center position, the spring 56, through its ends 54 and 58, exerts a force tending to rotate the hinge leaf 28 in a counterclockwise direction

about pivot pin 22 as viewed in Figure 7. Such rotation is prevented by the stop or strap 34 engaging with the inside of the re-entrant bend 38 in the hinge leaf 28. This stop 34 also serves to prevent the door being opened beyond a limited position so as to prevent damage to the hinges, the door pillar and the exterior sheet metal of the automobile body.

While the hinge 28 is moving from the position shown in Figure 5 to that shown in Figure 7, the spring 46, as shown in Figure 6, first has the tension relieved from it and then as it becomes slack, the end 44 moves from the position shown in Figure 6 to that shown in Figure 8 along the arcuate slot 42. In other words, the spring 46 is simply idling during the last portion of the opening movement of the door. It will be noted that in the open position of the hinge, the end 44 of the spring 46 does not contact the idle end of the slot 42 but is spaced therefrom. It should also be noted that the end 54 of the spring 56 (in the closed position of the door) is spaced from the lower end or idle of the slot 52 although in the case of either spring a light contact with the idling end of its respective slot would be permissible.

It will thus be seen that there has been provided a hinge which functions in a manner to prop the door open in two positions, fully open and half open, and that a retarding spring is provided which functions to prevent the acceleration of the door in its closing direction. It will be appreciated that these instrumentalities operate in the same fashion regardless of the inclination of the axis upon which the door is hinged. At the same time a stop is provided for preventing the door from swinging open beyond a safe position and for preventing the destruction or damage of the hinge, its anchorage or the exterior panels of the vehicle.

While the invention has been described in considerable detail, the description is not to be taken as limiting the invention. All equivalents falling within the scope of the appended claims are reserved.

What is claimed is:

1. A hinge comprising a base member, a pivot pin attached to said base member, a hinge leaf having one end journaled on said pivot pin, a first spring extending between said hinge leaf and said base member and opposing opening movement of said hinge as said hinge leaf is moved from closed position toward open position, a second spring extending between said hinge leaf and said base member and opposing closing movement of said hinge as said hinge is moved from open position toward closed position, and anchorages for each of said springs upon said leaf and base, one of said anchorages for each spring being elongated to provide lost motion in the anchorage.

2. A hinge comprising a base member, a pivot pin attached to said base member, a hinge leaf having one end journaled on said pivot pin, a first spring extending between said hinge leaf and said base member, a first set of anchorages for said first spring in said leaf and said base member, one of said first set of anchorages being elongated to provide lost motion between said spring and anchorage opposing opening movement of said hinge as said hinge leaf is moved from closed position toward open position, a second spring extending between said hinge leaf and said base member, and a second set of anchorages for said second spring in said leaf and base mem-

ber, one of said second set of anchorages being elongated to provide lost motion between said second spring and said second set of anchorages opposing closing movement of said hinge as said hinge is moved from open position toward closed position, said first elongated anchorage being so disposed as to induce no forces in said first spring in the open position of the hinge and said second anchorage cam surface being so disposed as to induce no forces in said second spring in the closed position of the hinge.

3. A hinge comprising a base member, a pivot pin attached to said base member, a hinge leaf having one end journaled on said pivot pin, a first spring extending between said hinge leaf and said base member and opposing opening movement of said hinge as said hinge leaf is moved from closed position toward open position and effective only through slightly more than the first half of said movement, a second spring extending between said hinge leaf and said base member and opposing closing movement of said hinge as said hinge is moved from open position toward closed position, said first spring being inoperative in the open position of the hinge and said second spring being inoperative in the closed position of the hinge, said springs being of the hairpin type and having ends anchored respectively in said hinge leaf and said base member, and slots constituting anchorages for said springs so disposed in said base member with respect to one another and to said pivot pin that each spring is effective and is stressed through slightly more than one-half the travel of said hinge leaf.

4. A hinge comprising a base member, a pivot pin attached to said base member, a hinge leaf having one end journaled on said pivot pin, a first spring extending between said hinge leaf and said base member and opposing opening movement of said hinge as said hinge leaf is moved from closed position toward open position, a second spring extending between said hinge leaf and said base member and opposing closing movement of said hinge as said hinge leaf is moved from open position toward closed position, said first spring being inoperative in the open position of the hinge and said second spring being inoperative in the closed position of the hinge, said springs being of the hairpin type and having ends anchored respectively in said hinge leaf and said base member, and slots providing anchorages for said springs in said base member to permit lost motion of each spring in one or the other direction of travel of the hinge as it approaches either open or closed position.

5. A hinge comprising a channel-shaped base member, a pivot pin extending from side to side of the channel and secured thereto, a hinge leaf journaled upon said pin and rotatable thereabout to and from closed and open position, spring seats formed in said hinge leaf, and hairpin springs each having one end anchored in one of said seats and another end anchored in one of two slots formed in said base member, said slots being arranged transverse to one another and so disposed with respect to said pivot pin that each spring is effective through slightly more than one-half the travel of said hinge leaf.

6. A hinge comprising a base including spaced parallel walls, a pivot pin extending between and secured to said walls, a hinge leaf extending into the space between said walls and journaled on said pivot pin, a slot in each of said walls, an aperture in each side of said hinge leaf adjacent each wall, and springs each having one end seated

in one of said hinge leaf apertures and its other end anchored in the base slot adjacent said one aperture, said slots being arranged generally transverse to one another and disposed at such a distance from said pivot pin that both springs are effective in the intermediate portion of the hinge leaf travel and one or the other spring is effective toward the limits of travel of the hinge leaf.

10 7. A hinge comprising a base including spaced parallel walls, a pivot pin extending between and secured to said walls, a hinge leaf extending into the space between said walls and journaled on said pivot pin, a slot in each of said walls, an aperture in each side of said hinge leaf adjacent each wall, and springs each having one end seated in one of said hinge leaf apertures and its other end anchored in the base slot adjacent said one aperture, said slots being arranged generally transverse to one another and disposed at such a distance from said pivot pin that each spring is effective through slightly more than one-half of the travel of the hinge leaf.

15 8. A hinge comprising a base including spaced parallel walls, a pivot pin extending between and secured to said walls, a hinge leaf extending into the space between said walls and journaled on said pivot pin, a slot in each of said walls, an aperture in each side of said hinge leaf adjacent each wall, and springs each having one end seated in one of said hinge leaf apertures and its other end anchored in the base slot adjacent said one aperture, said slots being arranged generally transverse to one another and disposed at such a distance from said pivot pin that each spring is effective through slightly more than one-half of the travel of the hinge leaf.

20 9. A hinge comprising a base, a pivot pin supported by said base, a hinge leaf journaled on said pivot pin for rotation thereabout to and from open and closed position, two over-centering springs having ends anchored in said hinge leaf and base respectively and so positioned with respect to said hinge leaf and base that said springs act in series first to oppose and then to assist in movement of the hinge leaf from one to the other of its limits of movement, and anchorages 25 for said springs comprising slots so disposed with respect to one another and to said pivot pin that each spring is stressed by a slot and is effective through slightly more than one-half the travel of said hinge leaf, each said spring being unstressed by its respective slot and idling therein during the remainder of the hinge leaf travel.

10 10. A hinge comprising a base, a pivot pin supported by said base, a hinge leaf journaled on said pivot pin for rotation thereabout to and from open and closed position, two over-centering springs having ends anchored in said hinge leaf and base respectively and so positioned with respect to said hinge leaf and base that said springs act in series first to oppose and then to assist in movement of the hinge leaf from one to the other of its limits of movement, the range of effectiveness of said springs overlapping at the central position of the hinge leaf in its movement so that each spring opposes movement in one direction of the hinge leaf away from its central position, and anchorages for said springs comprising slots transversely arranged with respect to one another and each receiving one end of one of said springs and so disposed with respect to said pivot pin that each spring is effec-

tively stressed to bias said hinge leaf only through slightly more than half the range of travel of said hinge leaf and each spring being so controlled in a different sector of said travel.

11. A hinge comprising a base member, a pivot pin attached to said base member, a hinge leaf having one end journaled on said pivot pin, a first resilient means extending between said hinge leaf and said base member and opposing opening movement of said hinge as said hinge leaf is moved from closed position toward open position, a second resilient means extending between said hinge leaf and said base member and opposing closing movement of said hinge as said hinge leaf is moved from open position toward closed position, said first resilient means being inoperative in the open position of the hinge and said second resilient means being inoperative in the closed position of the hinge, said resilient means both being effective and opposing one another in varying degree over a limited range in the half-open position of the hinge, and anchor-

ages for said springs including slots in said base member in which said springs idle during the ineffective portions of their ranges and which act to stress the springs in the effective portions of their ranges.

12. A hinge comprising a base member, a pivot pin secured to said base member, a hinge leaf journaled on said pivot pin and rotatable thereabout to and from open and closed position, a 10 pair of overcenter springs each extending between said base member and hinge leaf, each spring being effective in a different half of travel of said leaf from the other spring and each acting during movement of the hinge leaf first to oppose and then to assist said leaf as it is moved 15 from open to closed position or from closed to open position, and anchorages for said springs including slots in said base member in which said springs idle during the ineffective portions of their ranges and which act to stress the springs in the effective portions of their ranges.

THEODORE ULRICH.

CERTIFICATE OF CORRECTION.

Patent No. 2,335,201.

November 23, 1943.

THEODORE ULRICH.

It is hereby certified that error appears in the printed specification of the above numbered patent requiring correction as follows: Page 3, first column, line 24, claim 3, after "position" and before the comma insert --and effective only through slightly more than the first half of said movement--; and that the said Letters Patent should be read with this correction therein that the same may conform to the record of the case in the Patent Office.

Signed and sealed this 1st day of February, A. D. 1944.

Henry Van Arsdale,

(Seal)

Acting Commissioner of Patents.
